CLAIM

The ornamental design for a urine collection apparatus, as shown and described.

DESCRIPTION

FIG. 1 is a front perspective view of a urine collection apparatus;

FIG. 2 is an exploded front perspective view thereof;

FIG. 3 is a top view thereof;

FIG. 4 is a bottom view thereof;

FIG. 5 is a front view thereof;

FIG. 6 is a side view thereof;

FIG. 7 is a front view of only the top portion of the apparatus;

FIG. 8 is a front view of only the bottom portion of the apparatus;

FIG. 9 is a cross-section side view taken from FIG. 6 thereof;

FIG. 10 is a top view shown in a position for use; and, FIG. 11 is a front view shown in a position of use.

The broken lines in the drawings illustrate portions of the urine collection apparatus and form no part of the claimed design.
